SEWING MACHINE

Alfred B. Fowler, deceased, late of Beverly, Mass., by Mary F. Fowler, Beverly, Mass., administratrix, assignor to United Shoe Machinery Corporation, Paterson, N. J., a corporation of New Jersey

Original application June 11, 1926, Serial No. 115,202. Divided and this application October 15, 1931, Serial No. 569,026

3 Claims. (Cl. 112—48)

The present invention relates to machines for sewing soles to the uppers of boots and shoes and more particularly to that type known as lock-stitch McKay shoe sewing machines.

5 The object of the present invention is to provide a novel and improved feed mechanism particularly adapted for use in a lockstitch machine of the McKay type which is simple in construction and will operate accurately at high speeds.

10 In lockstitching machines of the general type herein described, the sewing instrumentalities are ordinarily adapted for making a stitch which is short as compared with the length of stitch employed in chain stitch machines. In these 15 machines, due to the high speed of operation, it is desirable to secure a positively acting feed movement so that the work feeding member will advance the work a uniform amount for each 20 stitch, and will engage the work firmly to prevent possible slippage during the feeding operation. With the construction herein disclosed, a work piercing awl is employed which is adapted to perforate the work in advance of the needle stroke and is also given a movement laterally 25 with relation to the needle to feed the work.

With the above mentioned and other objects in view, as will hereinafter appear, a principal feature of the present invention consists in the provision of a simple and efficient positive four 30 motion awl feed in which the awl is mounted to reciprocate in a carriage in the line of feed to bring the awl into line with the needle and is moved downwardly to perforate the work in advance of the needle stroke, the connections 35 for actuating the feed point and the feeding carriage being mounted on the machine frame and driven directly from the sewing shaft of the machine.

Other features of the invention consist in the 40 devices, combinations and arrangement of parts hereinafter described and claimed which, together with the advantages to be obtained thereby, will be readily understood by those skilled in the art from the following description taken 45 in connection with the accompanying drawings in which Fig. 1 is a front elevation of the head of a lockstitch McKay shoe sewing machine embodying the invention, and Fig. 2 is a right side elevation of the head of the machine.

50 The present application is a division of applicant's pending application Serial No. 115,202, filed June 11, 1926, for sewing machines, to which reference may be had for a more complete description of the machine.

55 The lockstitch McKay shoe sewing machine

herein disclosed as embodying the present invention includes a straight hooked needle, a work supporting horn of usual construction adapted to extend within the shoe and provided with the usual whirl to supply thread to the needle, and an awl which is given positive vertical and horizontal movements to perforate the work for the passage of the needle, and to feed the work to align the perforations accurately with the needle. The thread handling devices include a bobbin case and a loop taking hook, and an arrangement of thread locks, pull-off and take-up for the needle thread which are fully described and illustrated in the applicant's pending application above referred to.

60 Referring more specifically to the drawings which illustrate the head of the machine, the needle is indicated at 4, the awl at 6, the presser foot at 8, the bobbin case and loop taking hook at 10 and 12 respectively, and the work supporting horn cooperating therewith at 14. The sewing shaft 16 of the machine is driven from a source of power located in the base of the machine through driving connections as described 65 in the application above referred to.

70 The awl 6 is adjustably held in a clamp 18 on the lower end of the awl bar 20 which is mounted to slide vertically in brackets 22 on the feed slide 24. A pin 26 journalled in the upper end of the awl bar supports a block 28 which is adapted 75 to move in the slot 30 formed in the end of the lever 32 so that the awl bar is at all times operatively connected with the lever during the back and forth movement of the feed slide. The lever 32 is mounted on one end of the rock shaft 34 journalled in the machine frame. In order 80 to turn the rock shaft 34 and thus cause the awl to move to and from the work, the shaft is provided at its other end with a lever 36 which carries a cam roll 38 to engage a groove in the face 85 of the cam 40.

85 The feed slide is mounted to reciprocate on horizontal bars 42 fixed to the machine frame and is actuated from the cam 44 on the sewing shaft by means of a lever 46 having a fulcrum 90 at 48 on the machine frame and a cam roll 50 to engage a groove in the face of the cam. A sliding connection is provided between the lever 46 and the feed slide comprising a block 52 pivotally mounted on the lower end of the lever and designed to move in a vertical slot 54 formed on the rear side of the feed slide.

95 With this arrangement of the parts it will be seen that the awl is given two positive lines of movement, one to and from the work im- 100

110

parted by the lever 32 and its actuating mechanism, and the other back and forth in the line of feed with the feed slide, this movement being so timed that the awl is moved forward while in engagement with the work and is retracted after the awl has been withdrawn preparatory for punching another hole.

The needle is carried on the lower end of the vertical needle bar 56 which is supported by brackets 58 and 60 on the machine frame. A collar 62 fastened to the bar forms a pivotal support for the parallel links 64 which connect the needle bar to its actuating lever 66 pivoted on shaft 68. The sleeve 70 which forms the hub 15 of the needle lever 66 carries also the lever arm 72 with the cam roll 74 adapted to engage a cam groove in the periphery of the cam 40.

The presser foot 8 is adjustably mounted in a block 76 on the lower end of the presser foot bar 78 which is adapted to slide in brackets 80, 20 82 and 84 in the machine frame. The presser foot bar is forced down against the work by means of the spring 86 coiled about the bar between a collar 88 on the bar and the bracket 82, 25 the downward movement being limited by the engagement of the nut 92 on the upper end of the presser foot bar with the bracket 80.

Mechanism for lifting the presser foot is provided consisting of a collar 94 loosely mounted on 30 the presser foot bar and containing a bearing for the cam lever 96 having the eccentric cam surface 97 adapted to come into contact with a recessed surface 98 on the presser foot bar. The collar 94 is normally held in its lowest position 35 resting against the bracket 82 by means of a spring 99 coiled about the presser foot bar and inserted between the collar 94 and bracket 80. The cam lever 96 at its outer end engages the slot 100 in the presser foot lifting lever 102 which 40 is adjustably clamped to the rock shaft 104 by means of a split hub and the set screw 106. Another lever 108 attached to the rock shaft carries a cam roll 110 adapted to ride on the periphery of cam 40. As the lifting lever 102 45 is raised under the influence of the cam 40, the cam lever 96 is turned about its pivot causing the cam surface acting in conjunction with the collar 94 to grip the presser foot bar which is lifted a uniform distance against the pressure of the springs 86 and 99 to disengage the work.

At the end of the feeding operation, the shaft 104 is again rocked by the cam 40, allowing the presser foot to be forced down into clamping engagement with the work. A locking device 55 is provided to hold the presser foot bar in clamping position which comprises a roll 112 inserted between the inclined surface 114 and a slightly recessed surface 116 of the presser foot bar and held in yielding contact with these 60 surfaces by means of the spring plunger 118. In order to release the locking mechanism pre-

paratory to lifting the presser foot a lever 119 clamped to the rock shaft 120 by a split hub and set screw 122 is adapted to bear on the upper side of the roll and force it downward against the pressure of the spring plunger 118. The shaft 120 is rocked for this purpose by means of a lever 123 mounted on the shaft and having at its outer end a cam roll 124 to engage the periphery of the cam 40. A spring 126 stretched between a pin 128 on the lever 119 and a point on the machine frame tends to press the roll 124 against its cam and keeps the lever 119 normally out of engagement with the locking roll 112.

The invention having been thus described, what is claimed is:

1. A lockstitch sewing machine having, in combination, stitch forming devices including a straight hook needle, locking thread mechanism, a work supporting horn, a presser foot, a feed slide, an awl mounted on the feed slide to move towards and from the work, means for imparting to the awl uniform work piercing movements to form perforations in the work for the needle extending completely through the work, regardless of variations in its thickness, and means for actuating the feed slide to cause the awl to feed the work.

2. A lockstitch sewing machine having, in combination, stitch forming devices including a straight hook needle, locking thread mechanism, a work supporting horn, a presser foot, a feed slide, an awl mounted on the feed slide to move towards and from the work, means for imparting to the awl uniform work piercing movements to form perforations in the work for the needle extending completely through the work, regardless of variations in the thickness, and means for actuating the feed slide to bring the perforations successively into alignment with the needle.

3. A lockstitch sewing machine having, in combination, stitch forming devices including a straight hook needle, locking thread mechanism, a work supporting horn, a presser foot, a feed slide mounted to reciprocate in the line of feed on the frame of the machine, an awl mounted on the feed slide movable to perforate the work, a cam shaft, and connections for actuating the awl and the feed slide, said connections being mounted on the machine frame and driven directly from the said cam shaft to impart to the awl uniform work piercing movements to form perforations in the work for the needle extending completely through the work regardless of variations in its thickness, and to actuate the feed slide to bring the perforations successively into alignment with the needle.

MARY F. FOWLER,
Administratrix of the Estate of Alfred B. Fowler,
Deceased.
